UNITED STATES PATENT OFFICE.

ALONZO D. SEAMAN, OF MILWAUKEE, WISCONSIN.

SANITARY DRINKING DEVICE.

1,028,142.

Specification of Letters Patent.

Patented June 4, 1912.

Application filed June 28, 1910. Serial No. 569,364.

To all whom it may concern:

Be it known that I, ALONZO D. SEAMAN, a citizen of the United States, residing at Milwaukee, in the county of Milwaukee and 5 State of Wisconsin, have invented new and useful Improvements in Sanitary Drinking Devices, of which the following is a full, clear, concise, and exact description, reference being had to the accompanying drawing, forming a part of this specification.

My invention relates to a sanitary drinking device.

One of the objects of my invention is to provide a simple portable drinking device 15 which may be conveniently carried about, for example, in the pocket of the user.

It is well known that the use of the same drinking cup or glass by a number of people is unsanitary, particularly in factories or 20 other buildings in which a large number of individuals are employed, and in which the air may be filled with impurities. It is inconvenient and expensive to establish and maintain a number of stationary sanitary 25 drinking fountains throughout an establishment of this kind, or elsewhere, whereas the usual water faucets are often conveniently located at various points throughout an entire building, although accompanied usually 30 by a single drinking cup or glass.

I propose to provide each person with an individual tube of peculiar configuration but of inexpensive construction, by means 35 of which those who desire may readily connect with any convenient faucet or pipe to obtain an upwardly or outwardly flowing fountain or jet of water, and thus have all the advantages of the sanitary drinking stands found in the parks and other public 40 places.

While the invention may be embodied in a number of forms, I have illustrated in the accompanying drawings, a simple and practical embodiment of my idea.

45 In the drawings,—Figure 1 is a side elevation partly in section, of my sanitary drinking device applied to an ordinary faucet. Fig. 2 is a top view of the same. Fig. 3 is a sectional elevation.

50 My sanitary drinking device consists essentially of a main body or tubular portion 1, having preferably integrally formed therewith, at one end, an enlarged portion with a flaring mouth 2, and at the opposite 55 end an orifice or nozzle 3, although I do not limit myself to this construction. The

enlarged flaring mouth 2 is preferably provided with a resilient lining 4, which may be of rubber or other suitable material, and which corresponds substantially to the contour of the flaring mouth so as to fit therein and constitute a part of the drinking device. This resilient lining is adapted to form a tight joint when the drinking device is pressed against an ordinary faucet or pipe, as shown in Fig. 1. It is obvious 60 however that this lining is not essential, as the flaring mouth 2 could be pressed directly against the faucet, although by the use of the resilient lining a better joint, and one 65 that is practically water-tight, is secured.

In the preferred construction I prefer to arrange the flaring mouth portion 2 and the opposite end 3 substantially parallel to each other, the angle of the connecting body portion 1, being immaterial. This main body portion 1 could, of course, be arranged substantially at a right angle to either or both of the end portions although the arrangement shown in Fig. 1 is preferable owing to 70 the fact that the orifice portion or nozzle 3 is elevated some distance above the opposite end. The main body portion 1 may have a portion of reduced diameter 5 at the 75 end adjoining the nozzle portion 3. This is merely a structural feature however, incident to the bending of the tube at the junction of the two portions, where the tube is 80 made of metal, although I do not limit myself to this material as it is obvious that any 85 suitable material may be employed.

The device is applied by simply pressing the flaring mouth up over the end of the faucet 6, as shown in Fig. 1, whereupon when the water is turned on, it will pass 90 through the hollow member and issue from the nozzle 3 in a stream, the volume of which may be regulated at will by the valve 95 on the faucet.

In drinking, it is not necessary to touch 100 the device at all except to hold it in place, as the mouth may be placed directly over the issuing stream, at any convenient distance from the nozzle 3.

It is not necessary that the ends 2 and 3 105 should be parallel with each other, as it is obvious that a straight tube having a flaring mouth at one end and an upwardly extending nozzle portion at the opposite end, may be conveniently applied to a pipe or 110 faucet from which the water issues in a horizontal stream, one of the objects of the

invention being to provide a device of suitable configuration to fit a pipe or faucet from which the water issues at any fixed angle, and to direct the stream of water upwardly or outwardly from the mouth-piece, after conducting the water through a tube having whatever bends are necessary to accomplish the desired result in the simplest manner. In view of this fact, it will be apparent that it is not even necessary that the ends 2 and 3 lie in the same plane. However the form of device illustrated in the drawings is preferable under most circumstances.

From the foregoing it will be apparent that I do not limit myself to the details of construction shown and described, but desire to include broadly any equivalent means for accomplishing the desired result and coming within the scope of the appended claims.

Having described my invention, what I claim as new, and desire to secure by Letters Patent of the United States, is—

1. A portable sanitary drinking device having a flared end adapted to fit over a faucet or pipe to make a water-tight connection therewith by manual pressure directed in the line of the discharge, and having means for directing the stream of water from said faucet or pipe in an upwardly direction.

2. As a new article of manufacture, a portable sanitary drinking device comprising a unitary structure having a conical end adapted to coöperate with a faucet or pipe to make a water-tight connection therewith

when pressed against the same in the line of the discharge, and having means for directing the issuing stream of water in an upwardly direction.

3. A portable sanitary drinking device comprising a main hollow portion having a flaring mouth and a nozzle portion each of said portions being arranged at an angle to the main body portion, said flaring mouth portion being provided with a resilient lining adapted to be manually pressed against a faucet in the line of the discharge to make a water-tight connection therewith.

4. A portable sanitary drinking device consisting of a tubular member having at one end a flaring mouth portion provided with a resilient lining, said portion adapted to be held firmly against the downwardly extending end of a water faucet, said main body portion extending diagonally upward from said flaring mouth portion, and having at its opposite end a restricted portion and a nozzle portion beyond said restricted portion, said nozzle portion being arranged at an angle with said main body portion so as to extend substantially vertically upward, whereby the downwardly directed stream of water from said faucet is deflected and delivered as a vertical stream.

In witness whereof, I have hereunto subscribed my name in the presence of two witnesses.

ALONZO D. SEAMAN.
